ADJUSTABLE CAM TRACK

John W. Neff, Easton, Pa., assignor to Binney and Smith Company, New York, N. Y., a corporation of New Jersey

Original application February 24, 1941, Serial No. 380,373. Divided and this application May 8, 1942, Serial No. 442,244

6 Claims. (Cl. 74—568)

This invention relates to cams of the track type and has for an object to provide a cam and follower mechanism in which means are provided for effecting relative adjustment between the cam and its follower so as to raise or lower the path of reciprocating movement of the follower. The present application is a division of my earlier application, Serial No. 380,373, filed February 24, 1941.

More particularly the invention has for an object to provide a cam and follower adapted to be mounted for relative rotation, the cam having a transversely-inclined eccentric track, and means for effecting lateral movement between the cam and its follower so as to cause the follower to contact higher or lower points upon the cam track.

Another object of my invention is to provide in a cam and follower mechanism a pair of cams of the above character having slots defining transversely inclined endless tracks of corresponding contours opening through their opposed faces, a follower bar extending between and having its ends engaging the pair of tracks, and means for simultaneously and uniformly adjusting the cams toward and from each other to vary the position of the follower on the sloping tracks and consequently to raise or lower the path of reciprocating movement of the follower.

Still another object of my invention is to provide a track cam of the above character comprising a series of arcuate cam sections detachably secured together to permit the replacement of certain sections as they become worn or in order to change the contour of the track.

Other objects and advantages will be apparent from the following detailed description of a preferred embodiment of the invention, reference being had to the accompanying drawings, in which:

Figure 1 is a longitudinal cross-sectional view through a rotary molding machine designed for producing wax crayons and employing a pair of stationary but laterally adjustable cam rings for actuating the followers supporting the rows of plungers associated with the crayon molds;

Figure 2 shows schematically the sprocket and chain mechanism for simultaneously adjusting the cam rings toward and from each other;

Figure 3 is a full face view of one of the cam rings;

Figure 4 is a transverse cross-sectional view of the cam ring taken on the line 4—4 of Figure 3;

Figure 5 is a transverse cross-sectional view

of the cam ring taken on the line 5—5 of Fig. 3;

Figure 6 is a detail view of the outer face of the cam ring showing the manner in which its arcuate sections are held in assembly;

5 Figure 7 is a transverse cross-sectional view through a cam ring showing one of the cam-adjusting screws;

Figure 8 is a fragmentary face view of a track cam showing the cam-adjusting screw viewed from the left-hand side of Figure 7; and

10 Figure 9 is a lineal development of the track of the cam of Fig. 3.

In the drawings is illustrated a continuous rotary molding machine adapted for casting sticks

15 of wax crayon, and exemplifying one type of machine with which the cam mechanism constituting the subject of the present invention may be successfully employed. This machine in general comprises a cylindrical mold carrier M supported for rotation on stanchions 1 and 2, and circumferentially provided with longitudinal rows of radially-disposed tubular molds 3. A pair of stationary track cams 4 is located adjacent opposite ends of the mold carrier and a

20 follower bar 5 extends between the cams and travels within their tracks during rotation of the mold carrier. Plungers 10 connected to the follower bars and slideable within the molds 3 serve to eject the sticks of crayons from the molds

25 in a step-by-step movement. A knife 6 fixed to a support 7 is adjustable circumferentially about the interior of the mold carrier so as to trim off the projecting ends of the crayons, thus determining the lengths of the crayons finally ejected

30 from the molds.

35 Projecting circumferentially outward from the mold carrier at its opposite ends are flanges 8. These flanges are radially slotted at circumferentially spaced intervals to provide guideways for

40 the follower bars 5. Each follower bar supports the outer ends of a row of plungers 10 associated with a corresponding row of molds on the mold carrier. Upon the ends of the follower bars are rotatably mounted rollers 11 extending 45 into slots defining endless tracks 12 upon the opposed side faces of the cams 4. Each cam is composed of two major parts, a central cam support 13 and an encircling and laterally shiftable cam ring 14.

50 The tracks 12 of the pair of cams are of a corresponding contour, and this contour will be determined by the character of the impulses to be imparted to the follower bars and for certain purposes may take the form illustrated in Fig. 3.

55 A lineal development of this cam track is

schematically represented in Fig. 9. For the major portion A of its length, the track is concentric with the axis of rotation of the mold carrier and is most distantly located therefrom. Throughout a succeeding portion B the track slopes inwardly toward the axis in a series of concentric stepped sections ultimately attaining its closest approach to the axis where, throughout a short angular distance C, it extends concentrically with the cam. Thereafter the track for a portion D is inclined sharply upward and joins the concentric portion A, thus completing its contour.

The effect of this form of cam upon the plungers supported by the follower bars is as follows: During rotation of the mold carrier M throughout that part of its circle of travel corresponding to the portion A of the cam tracks, the row of plungers 10 connected to a follower bar are sustained in their fully retracted position. As the follower bar moves through an angle corresponding to the portion B of the cam tracks, the plungers are moved radially inward in an interrupted movement so as to progressively project the cast crayon sticks from a row of molds. Then as the mold carrier moves through the portion C, there is a short period of dwell. Continued movement of the mold carrier through an arc corresponding to the portion D of the cam tracks causes the plungers to be quickly retracted.

The cam and follower mechanism for accomplishing the above movement of the plungers will now be more particularly described. The cam ring 14 of each cam is composed of a plurality of arcuate segments secured together in the manner indicated in Fig. 6. Adjacent the ends upon the outer face of each cam segment (that is, upon its face opposite to that through which the cam track opens) are upstanding flanges 15 and bolts 16 extending through openings in the opposed flanges of abutting segments to clamp the segments together. By reason of this sectional cam construction, the cams may be conveniently shipped in knock-down condition, while worn or damaged sections may be quickly replaced by new ones as occasion requires.

The cam tracks 12, at least for the major portion of their length, are disposed on a slope, as indicated in Fig. 4. That is, the upper and lower walls 12a and 12b of the tracks are transversely inclined so that when the cam rings are shifted toward and from each other, rollers 11 supporting the ends of a follower bar 5 are caused to contact higher or lower points upon the sloping tracks. Each roller is supported on a spindle 9 extending from an end of the follower bar being intermediately inclined at approximately the same inclinations as the cam track.

By laterally varying the position of the cams the sequence or pattern of operation of the followers, and hence the plungers supported thereby, remains unchanged, although the location of the plungers with respect to their companion molds for corresponding positions of the mold carrier is altered—that is, the working range of the plungers is raised or lowered. In order that the plungers will not be projected beyond the inner ends of the molds in any position of adjustment of the cams, the walls 12a and 12b of the arcuate portion C of the tracks, representing the maximum approach of the rollers toward the axis of rotation of the mold carrier, are made horizontal or level, as indicated in Fig.

5. Likewise the walls of the plunger-retracting portion D of the cam tracks leading from the innermost to the outermost circular contours of the tracks are made horizontal.

5 The transverse slope or pitch of the walls of the tracks of both cams in equal and uniform, and in order to insure the proper operation of the plungers supported by the follower bars it is necessary that the adjustments of the cams toward and from each other should occur simultaneously and in equal increments of movement so as to maintain the follower bars horizontal for any position of adjustment of the cams. To accomplish this, the inner circumference of each cam ring is notched, as indicated at 18, at angularly spaced intervals (Fig. 3), and fitted within each notch and secured in place by bolts 19 are blocks 20 (Figs. 7 and 8) having a screw-threaded, semi-cylindrical recess 21. The cam support of each cam is likewise provided, at points corresponding to the notches 18 on the cam ring, with clearance recesses 22, in each of which there is rotatably mounted a worm 23 engaging the threads of the block 20. Each worm has a stem 24 extending from the clearance recess to the outer face of the cam and upon its end is fixed a sprocket 25. As schematically represented in Fig. 2, an endless chain 26 winds over all the series of sprockets 25. For driving these chains an operating bar 27 extends horizontally above the machine, and this operating bar carries sprockets 28 which are respectively connected through chains 29 with sprockets 30 paired with sprockets 25 on two of the stems 24. By connecting a hand-crank K to a squared end of the operating bar, this shaft may be rotated to likewise rotate all the worms 23, through the transmission chains just described, for simultaneously shifting the cam rings toward or from each other.

40 The function of the cams in the machine just described is as follows: For any fixed position of the cams, the stepped contour of the cam tracks allow for the production of only a relatively few selected lengths of crayons, depending upon the adjustment of the trimming knife. In order to meet the demands of the trade, however, it is desirable that crayons should be made accurately to any desired length, within reasonable limits. 45 For accomplishing this object, the walls of the cam tracks 12 are disposed on a slope, as has already been explained, so that by uniformly and simultaneously adjusting both cams toward or from each other, the rollers 11 supporting the ends of the follower bars are caused to engage lower or higher points upon the sloping cam tracks.

50 For example, when the cams are moved closer together by rotating the operating bar 27, the rollers contact lower points transversely of the tracks and hence, during rotation of the mold carrier, they follow a path of smaller diameter. As a consequence, the plungers connected to the follower bars repeat the same pattern or sequence of operations, although their working range is altered with reference to a fixed point upon the molds (or, similarly stated, with reference to the axis of rotation of the mold carrier). Thus, when the cams are moved closer together 55 a greater length of crayon is caused to be projected from the molds during the period in which the rollers engaged the stepped portion B of the cam tracks. The machine accordingly is capable of producing crayons of any desired lengths within its capacity by making a few simple ad-

justments. Because the spindles 9 carrying the rollers are inclined at approximately the same slope as the track, the rollers may pass without obstruction to the full depth of the slots defining the tracks.

While the cam mechanism has been described above in conjunction with a crayon molding machine, this is merely by way of example, and it is contemplated that the cam mechanism will find useful application in other types of machines in which accurately variable adjustments of the path of travel of a follower member is necessary or desirable.

Obviously various changes in the form, construction, arrangement, and combination of the several parts of my new cam mechanism may be made and substituted for those herein shown and described without departing from the nature and principle of my invention as defined by the following claims.

I claim:

1. In a cam and follower mechanism, a pair of cams adapted to be stationarily supported in parallel relation, a pair of slots defining endless cam tracks of corresponding stepped contours opening through the opposed side faces of the cams, a follower extending between said slots and adapted to travel upon said tracks, said tracks sloping in reverse directions transversely of the cams, and means for simultaneously and uniformly adjusting the cams toward and from each other to raise or lower the position of the follower along the sloping cam tracks.

2. In a cam and follower mechanism, a circular cam support, a cam ring encircling said cam support for shifting movement transversely thereof, a slot defining an endless cam track opening through a side face of said cam ring, a follower adapted to enter the slot and travel upon said track, said track sloping in a direction transversely of the cam ring, and screw threaded means for shifting the cam ring transversely of the support to cause the follower to engage higher or lower points upon the cam track.

3. A cam comprising a circular cam support, a cam ring encircling said support for shifting movement transversely thereof, a slot defining an endless cam track opening through a side face of said cam ring, said track sloping in a direction transversely of the cam ring, and a plurality of screws rotatably mounted upon the support and engaging the cam ring for shifting the cam ring transversely of the support.
- 5 4. A cam comprising a circular cam support, a cam ring encircling said support for shifting movement transversely thereof, a slot defining an endless cam track opening through a side face of said cam ring, said track sloping in a direction transversely of the cam ring, a plurality of screws rotatably mounted upon the support and threadedly engaging the cam ring, and an operating member connected to all of said screws for simultaneously rotating the screws for shifting the cam ring transversely of the support.
- 10 5. A cam comprising a circular cam support, a cam ring encircling said support for shifting movement transversely thereof, a slot defining an endless cam track opening through a side face of said cam ring, said track sloping in a direction transversely of the cam ring, a plurality of screws rotatably mounted upon the support and threadedly engaging the cam ring, sprockets associated with said screws, a chain extending between the sprockets, and a manual operating member for moving the chain to simultaneously shift the cam ring transversely of the support.
- 15 6. A cam comprising a circular cam support, a cam ring encircling said support for shifting movement transversely thereof, said cam ring being composed of a plurality of arcuate sections detachably connected together, a slot defining an endless cam track opening through a side face of said cam ring, said track being sloped in a direction transversely of the cam ring, and a plurality of screws rotatably mounted upon the support and engaging the cam ring for shifting the cam ring transversely of the support.
